UNITED STATES PATENT OFFICE.

HERMANN E. WESCHÉ, OF PHILADELPHIA, PENNSYLVANIA, ASSIGNOR TO
ROBERT WOOD AND THOMAS S. ROOT, OF SAME PLACE.

DESIGN FOR AN URN AND PEDESTAL.

Specification forming part of Design No. **7,599**, dated July 28, 1874; application filed June 5, 1874.
[Term of Patent 7 years.]

To all whom it may concern:

Be it known that I, HERMANN E. WESCHÉ, of Philadelphia, Pennsylvania, have invented a Design for an Urn and Pedestal, of which the following is a specification:

The figure in the accompanying clearly represents my design, the principal members of which are the urn A and its pedestal B. The base *a* and stem *b* of the urn, are of the general form shown, and are perfectly plain, but the body *d* is elaborately ornamented, as follows: The lower projecting portion *e* of the body is scalloped, as shown, and from this portion to the overhanging ornamented lip *f*, at the top of the urn extend two handles, *g g*, which are of a foliated scroll-like character throughout, and are prominent features of the design. At about the center of the body *d* of the urn is a medallion, *h*, representing a female head and bust, surrounded by foliated ornamentation of the character represented. The pedestal B is rectangular, has two orna-

mented cornices, *i* and *k*, a foliated ornament or ornaments, *l*, and pieces projecting diagonally from each of its four corners, each consisting of a base, *m*, scroll-like bracket *n*, and cap-piece *p*, both the latter and the bracket being profusely ornamented, while the base is plain.

I claim as my invention—

1. The design for the urn A, as described and represented.
2. The design for the pedestal B, as shown and described.
3. The whole design, including the urn A and its pedestal B, as described, and represented in and by the accompanying drawing.

In testimony whereof I have signed my name to this specification in the presence of two subscribing witnesses.

HERMANN E. WESCHÉ.
